UNITED STATES PATENT OFFICE.

JOSEPH FORSHEIM, OF NEW YORK, N. Y., ASSIGNOR TO AMERICAN WHEEL COMPANY, OF NEW YORK, N. Y., A CORPORATION OF NEW YORK.

DESIGN FOR A DIAL FOR GAME APPARATUS.

No. 37,761.

Specification for Design.

Patented Dec. 26, 1905.

Application filed November 23, 1905. Serial No. 288,820. Term of patent 7 years.

To all whom it may concern:

Be it known that I, JOSEPH FORSHEIM, a citizen of the United States, and a resident of the borough of Manhattan, in the city and State of New York, have invented a new, original, and ornamental Design for a Dial for Game Apparatus, of which the following is a specification, reference being had to the accompanying drawing, forming a part thereof.

My new, original, and ornamental design for

a dial for game apparatus is shown in face view in the accompanying drawing.

I claim—

The ornamental design for a dial for game apparatus as shown.

JOSEPH FORSHEIM.
